[75] Inventors: **William E. Bartasevich, Kent; John J. Andrisin, III, Akron; John J. McEllen, Chagrin Falls, all of Ohio**

Primary Examiner—Susan J. Lucas
Attorney, Agent, or Firm—Rogers & Killeen

[73] Assignee: **Advanced Lighting Technologies, Inc., Solon, Ohio**

[57] CLAIM

The ornamental design for the lampholder assembly with integral ballast for a standing lamp, as shown.

[**] Term: **14 Years**

DESCRIPTION

[21] Appl. No.: **78,976**

FIG. 1 is a perspective view;

[22] Filed: **Nov. 5, 1997**

FIG. 2 is a top plan view;

[51] LOC (6) Cl. **26-99**

FIG. 3 is a bottom view;

[52] U.S. Cl. **D26/113; D26/138**

FIG. 4 is a front view;

[58] Field of Search **D26/24, 61, 63,**

FIG. 5 is a right-side view;

D26/65, 138, 140, 93, 102-112; 362/269,

FIG. 6 is a rear view; and,

275, 285, 287, 418, 419, 427, 428, 430,

FIG. 7 is a left-side view.

226, 410-414, 401, 402; 315/56, 58, 362
